COMBINED CHAIR AND FOLDABLE TABLE UNIT

Robert H. Ensign, Bronxville, N.Y., and Danforth Cardozo, Jr., Weston, Conn., assignors to Clarence Epstein, Orford, N.H.

Filed Dec. 4, 1957, Ser. No. 48,780

Term of patent 14 years

(Cl. D33—11)

FIG. 1.

FIG. 2.

FIG. 3.

Figure 1 is a perspective view of a combined chair and foldable table unit as seen from a position off to the left side and somewhat in front;

We claim:

The ornamental design for a combined chair and foldable table unit, substantially as shown.
